VACUUM CLEANER

Emanuel Nielsen and Arthur W. Seyfried, Racine,
Wis., assignors to Scovill Manufacturing Company,
Waterbury, Conn., a corporation of
Connecticut

Application February 1, 1941, Serial No. 376,984

3 Claims. (Cl. 15—16)

This invention relates to vacuum cleaners and particularly to a portable cleaner provided with a tiltably mounted, counterbalanced motor-nozzle unit in which the nozzle automatically adjusts itself relatively to the surface to be cleaned.

It is desirable to adjust the nozzle vertically with respect to the surface to be cleaned, depending on the thickness and character of the surface, in order to place the nozzle into position for efficient operation without being pulled down too closely to the surface to be cleaned.

Another object is to provide means for counterbalancing the weight of the handle in its various operative positions. We have found that there is a tendency for the nozzle to be raised from the surface to be cleaned when the handle, carrying the dust bag, is moved rearwardly and lowered to allow the cleaner to move under furniture, and therefore have provided means for automatically maintaining the nozzle in proper operative position, regardless of the position of the handle.

Another object is to provide a cleaner adapted to move easily over uneven surfaces and carpets of varying thicknesses.

The cleaner herein described automatically meets the requirements presented by the varying types of surfaces to be operated upon, by the provision of a motor and nozzle unit pivotally mounted on a transverse axis, the weight of the unit rearwardly of the pivotal mounting exceeding the weight forwardly thereof, together with the provision of yielding counterbalancing means tending to urge the forward portion of the nozzle toward the surface to be cleaned but without permitting excessive sink of the nozzle, and means for counterbalancing the weight of the handle and dust bag and its effect on the nozzle position when the handle is being moved relatively to the cleaner.

In the drawings:

Fig. 1 is a side elevation of a vacuum cleaner embodying our invention.

Fig. 2 is a plan view, partly in section, in the plane of the line 2—2 of Fig. 1, on a larger scale than Fig. 1.

Fig. 3 is a bottom plan view of the cleaner, as viewed from the plane of the line 3—3 on Fig. 5.

Fig. 4 is a plan view of part of the nozzle-motor unit supporting means, partly in section, in the plane of the line 4—4 of Fig. 1.

Fig. 5 is a side elevation of the cleaner, showing the handle and dust bag in lowered position.

Fig. 6 is a transverse vertical sectional view taken in the plane of the line 6—6 of Fig. 1.

Fig. 7 is a longitudinal vertical sectional view taken in the plane of the line 7—7 of Fig. 4.

Fig. 8 is an enlarged sectional view of a detail shown in Fig. 6.

In that embodiment of the invention shown in

the drawings, the cleaner comprises an integral motor casing 10, fan housing 11 and suction nozzle 12. A handle 13 provided with curved spread apart arms 14 is fixedly mounted on the square ends 15' of a shaft 15 beneath the motor casing 10 and retained by nuts 16. Said shaft 15 is pivotally mounted in a pair of apertured lugs 17 which depend rigidly from the motor-nozzle unit. Thus pivotal movement of the handle 13 relatively to the cleaner results in rotative movement of the shaft 15. A clip 18 having a slot 19 to receive the pin 20 on one of the arms 14 is mounted for limited sliding movement on said arm 14 of the handle so that the clip can be moved into and out of position to contact with a stop 21 fixedly secured to one side of the motor-nozzle unit. In its upward position, the clip 18 clears the stop 21 and allows the handle to be moved downwardly to the fullest extent.

20 A dust bag 22 is detachably secured to the nozzle 12 and to the handle 13 in a conventional manner.

The nozzle 12 has a brush 23 rotatably mounted adjacent the mouth of the nozzle which is partially closed by a removable shield 24 which is adapted to glide on and move smoothly over the surface to be cleaned. The shield and size of the openings therein, defining the mouth of the nozzle, are designed to coact with the nozzle supporting means to control the degree of sink of the nozzle relatively to the carpet surfaces.

At each side of the nozzle, rearwardly of the nozzle mouth, are casting extensions 25 in which are rigidly mounted generally S-shaped members 26. The members 26 provide vertically disposed walls between which are rotatably mounted the wheels 27, 27 and 28, 28, on short fixed shafts 29, 29, 30, 30, respectively. The shafts 29, 29 are in alignment with each other and the shafts 30, 30 are also in alignment with each other, but are located slightly rearwardly of the shafts 29. The wheels 27, 28 are thus rotatably mounted in the nozzle, their axes being fixed and so located that the treads of the wheels extend slightly below the edges of the walls of the nozzle 12 and normally in a plane about $\frac{1}{16}$ inch below the lower surface of the shield 24.

The weight of the motor-nozzle unit 10, 11, 12 is greater rearwardly of the shafts 30, 30 than forwardly of them, and if the motor casing or rearward portion were not supported as herein-after explained, said rearward portion would automatically drop, the unit would pivot about the axis of the shafts 30, 30, and the forward or mouth portion of the nozzle would be raised. The wheels 27 would also be raised. However, the excess weight rearwardly of the shafts 30 has been counterbalanced in such manner that the nozzle is almost constantly being supported by both sets of wheels 27, 27 and 28, 28.

The counterbalancing means just mentioned comprises a rear wheel-carrying plate 31 having upturned side flanges 32 pivotally connected at their forward portions by screws 33 to the motor casing 10. Rear wheels 34, 34 are rotatable on a shaft 35 fixedly mounted in the flanges 32 of the plate 31. A wire spring 36 is coiled on the shaft 15, one end of the spring being connected to the shaft by any suitable means such as the headed screw 37, and the other end 38 extending rearwardly under the motor casing 10 and plate 31, then through the slot 39 in said plate, over the shaft 35 and plate 31 and through an aperture in the upturned end 40 of the plate 31.

The function and effect of the spring 36-38 is to urge the plate 31 and wheels 34 away from the motor casing 10; in other words, to raise the motor casing relatively to the surface on which the device is standing and to counterbalance the greater weight of the rearward end of the unit. Another function is to cooperate with the shaft 15 on which the handle arms 14 are fixed, to urge the shaft to rotate counter-clockwise, as viewed in Figs. 1 and 5, so that the handle will be retained normally in a substantially vertical position, as shown in Fig. 1.

Another function of the spring 36-38 and parts to which it is connected is to counterbalance the weight and leverage of the handle 13 when it is moved from its perpendicular position to one of several positions it may occupy in the operation of the cleaner. This involves not only the handle, *per se*, but also the dust bag which, when inflated and the handle is in downward position, as when operating under furniture, pulls the nozzle portion upwardly. To prevent the weight and leverage of the handle and attached dust bag from unbalancing the pivoted unit, we have provided the spring 36 connected to the shaft 15 so that as the handle is moved downwardly, rearwardly, the shaft 15 rotates and the spring becomes coiled more tightly about the shaft, placing additional tension on the end 38, resulting in extra tendency to raise the motor casing 10 and to keep the nozzle 12 in efficient operative position on the surface to be cleaned.

The provision of two sets of wheels in the nozzle, located in different vertical planes, is a preferred feature of construction which aids in controlling the degree of sink resulting from the suctional effect of the operation of the cleaner, and which also facilitates smooth gliding of the nozzle over uneven surfaces. It is desirable to have wheels as far forwardly or close to the nozzle lips as possible to insure easy operation, but if the wheels are relatively far forwardly of the handle pivot, there is too great a tendency for the nozzle to be raised on the forward stroke. The tendency of the nozzle to rise on the forward stroke varies, being influenced by the resistance the floor covering offers to the cleaner on the forward stroke, and by the distance between the pivotal mountings of the handle and the cleaner body. The provision of a second pair of nozzle wheels mounted the correct distance forwardly of the handle pivot insures easy operation of the nozzle with a slight lifting effect on the forward stroke but without undue raising of the nozzle.

The provision of a carefully balanced motor-nozzle unit, pivotally mounted for self-adjustment, and having means for counterbalancing

the leverage weight of the handle and dust bag in their varying operative positions, is the essential feature of our invention, which results in a cleaner capable of cleaning bare floors as well as light, medium and thick rugs with equal ease.

Changes made be made in details of construction without departing from the scope of our invention.

We claim:

1. A vacuum cleaner comprising a motor and nozzle unit, a handle pivotally connected to said unit, means pivotally supporting the motor and nozzle unit, the said unit being heavier rearwardly of said pivotal supporting means than forwardly thereof, means supporting and movably connected with the rearward portion of the unit and means operatively connected to the handle and to the rearward supporting means yieldingly counterbalancing the weight of the unit and the leverage weight of the handle in its different operative positions, said counterbalancing means comprising a transverse shaft to which said handle is rigidly connected and a spring connected at one end to and coiled on said shaft, the other end of the spring bearing on the said means supporting the rearward portion of the motor and nozzle unit.

2. A vacuum cleaner comprising a motor and nozzle unit, a handle pivotally connected to said unit, means pivotally supporting the motor and nozzle unit, the said unit being heavier rearwardly of said pivotal supporting means than forwardly thereof, means supporting the rearward portion of the unit and means operatively connected to the handle and to the rearward supporting means yieldingly counterbalancing the weight of the unit and the leverage weight of the handle in its different operative positions, said means supporting the rearward portion of the unit comprising a plate pivotally connected to the motor portion of the unit and wheels rotatably carried by the plate rearwardly of said pivotal connection, and said counterbalancing means comprising a transverse shaft to which said handle is rigidly connected and a spring connected at one end to and coiled on said shaft, the other end of the spring bearing on said rear wheel carrying plate.

3. A vacuum cleaner comprising a motor and nozzle unit, a handle pivotally connected to said unit, means pivotally supporting the motor and nozzle unit, the said unit being heavier rearwardly of said pivotal supporting means than forwardly thereof, means supporting and movably connected with the rearward portion of the unit, and spring means between the rearward supporting means and said unit and operatively connected with said rearward supporting means and handle for counterbalancing the unbalanced weight of the unit rearwardly of the pivotal supporting means when the handle is in substantially perpendicular position, said counterbalancing means being automatically placed under increased tension when the handle is moved rearwardly and downwardly, whereby its counterbalancing effect is enhanced to compensate for the added weight disposed rearwardly of the pivotal supporting means for the unit.
